UNITED STATES PATENT OFFICE.

FRANK Z. SHERER, OF MONTCLAIR, NEW JERSEY.

WATER-TUBE BOILER.

No. 840,093.

Specification of Letters Patent.

Patented Jan. 1, 1907.

Application filed May 26, 1906. Serial No. 318,801.

To all whom it may concern

Be it known that I, FRANK Z. SHERER, residing at Montclair, in the county of Essex and State of New Jersey, have invented certain new and useful Improvements in Water-Tube Boilers, of which the following is a full, clear, and exact description, such as will enable others skilled in the art to which it appertains to make and use the same.

10 My invention relates to steam-generators, and more particularly to steam-boilers of the water-tube type.

One of the objects thereof is to provide a boiler of the above type characterized by increased efficiency.

Another object of my invention is to provide a safer and more reliable water-tube boiler than has hitherto been constructed and one, moreover, that combines economy 20 of construction, merchandising, and installing with a low cost of maintenance.

Other objects will be in part obvious and in part pointed out hereinafter.

The invention accordingly consists in the 25 features of construction, combinations of elements, and arrangement of parts, which will be exemplified in the embodiment hereinafter described, and the scope of the application of which will be indicated in the following claims.

In the accompanying drawings, wherein is shown one of the various possible embodiments of my invention, Figure 1 is a side elevation thereof, some of the parts being 35 shown in section. Fig. 2 is a front elevation of the same, with a portion of the fire-front removed, showing headers of the sinuous type and their connections with the front steam and water drum. Fig. 3 is a vertical 40 sectional view of the same, taken on line 3-3, Fig. 1. Fig. 4 is a view in perspective of a sinuous form of header that may be employed in a boiler constructed in accordance with my invention. Fig. 5 is a view in perspective of a box form of header that may be 45 employed in a boiler constructed in accordance with my invention. In this form the holes for the water-tubes are placed on a common center, one directly above the other, 50 the staggering of the various horizontal rows being accomplished by the transverse inclination of the headers placed side by side consecutively.

Similar reference characters refer to similar parts throughout the several views of the 55 drawings.

Preliminary to a description of the structural features of my invention and in order to render certain of the important objects thereof more intelligible it may here be noted that in the interest of safety as well as to secure minimum cost of maintenance of steam-generators the steam and water should be confined in as many and as small envelopes as possible or, in other words, that the generator should be sectionalized to the greatest possible extent. This is also important from the standpoint of convenience of handling in construction, transportation, and erection, and, moreover, there is secured by such construction a greater adaptability to meet special requirements as to location, character of fuel, and the further manifest advantage of securing large capacities from single built-up units. By my invention, one embodiment of which I shall presently describe more in detail, it will be apparent that I have attained the above and other desirable ends in a simple and efficient manner.

Referring now to the drawings, wherein I 80 have shown a preferred adaptation of my invention, 1 indicates the usual masonry base, which forms a part of the setting of the boiler and which supports the front wall 2, the rear wall 3, the side walls 4, and bridge-wall 5. The grate-bars 6 are suitably supported between the front wall 2 and the bridge-wall 5 and extend over the ash-pit 7. The combustion-chamber of the furnace is shown at 8. This particular construction 85 of the boiler-setting, however, comprises no essential part of my present invention and may be modified or changed in various ways to meet special requirements.

The water-tubes 9 run lengthwise of the 95 furnace and, as shown, are disposed in staggered relation in vertical rows, and the several tubes constituting each staggered row are connected in the usual ways at their ends with sectional headers 10. The outer walls 100 of the sectional headers are provided with the usual hand-holes 11 for furnishing access to the several water-tubes, said hand-holes being closed by hand-hole plates 12, secured in place, with the usual crabs, by bolts 13.

Extending transversely of water-tubes 9, above the sectional headers 10 at either end of the boiler, are steam and water drums 14 and 15, respectively, which are connected to each of the sectional headers by means of 105 tubes or nipples 16.

In order to provide for a circulation of wa-

ter between drums 14 and 15, I arrange therebetween a series of equalizer pipes or tubes 17, preferably in one or more horizontal rows. Said tubes may be completely submerged or partly below and partly above the usual water-line in the drums. The entire series of water-tubes 9, connecting the sectional headers, are inclined toward the rear to facilitate the proper circulation of water therethrough.

Located between the steam and water drums 14 and 15, disposed parallel thereto and having its center at a somewhat higher level, is a steam-drum 18, provided with steam-outlet 19. This steam-drum is connected with each of the steam and water drums 14 and 15 above the water-line by means of pipes or tubes 20, which can be arranged in one or more horizontal rows, according to the amount of surface required, in order to secure the desired degree of superheat in the steam, which is conducted by said tubes from the steam and water drums to steam-drum 18. I also connect the lower portion of steam-drum 18 with steam and water drum 15 by means of pipe 21, the function of which pipe is to drain any water of condensation which may be present in the steam-drum. This pipe may, however, be dispensed with, if desired. The roof 22, of tile or other material, is laid immediately above steam-tubes 20.

While the flue partitions or baffles to direct the course of the flames and heated gases can be arranged in any desired manner, I preferably provide vertical partitions or baffles 23 and 24, one of which is located immediately behind the grate-bars and one between that point and the rear ends of the water-tubes. The heated gases from the grate-bars 6, passing upward through the series or bank of water-tubes 9, sweep down between the vertical baffles 23 and 24 into the combustion-chamber 8, whence they pass between vertical baffle 24 and the rearmost series of sectional headers 10 to the smoke-outlet 25, or, if desired, the course of the gases traveling upward from the combustion-chamber may lead between the vertical baffle 24 and the rear sectional headers to a smoke-outlet located between the tubes or nipples which connect said sectional headers to the rear steam and water drum, and the smoke-outlet may, if desired, be otherwise located by means of special provision or arrangement of baffling.

Connected with each of the rear sectional headers 10 by means of tubes 26 is a mud-drum 27, to which access may be had by means of hand or man holes 28, normally closed by means of the usual crabs 29 and bolts 30. The boiler, however, may be used, if desired, with or without such mud-drum.

Suitable orifices are provided in the side

walls of the masonry structure of the setting of the boiler, through which soot may be removed. It will also be understood that the usual safety-valve, steam and water gages, blow-off pipes, and other usual boiler accessories may be provided, such accessories not being shown herein, as they comprise no essential part of my present invention.

It will accordingly be apparent that I have provided a construction well adapted to attain the several objects and ends of my invention and that by reason of such construction great economy in manufacture, assembling, and maintenance is secured. The steam and water drums and the steam-drum may be constructed entirely independent of the other elements comprising the boiler, as they are merely cylindrical shells. Each of the sectional headers is in itself a separate unit, and in case of one failing in service replacement could be readily made with but nominal expense. It will also be seen inasmuch as the steam-and-water drums and steam-drums are constructed of cylindrical shells that their length may be easily varied so as to accommodate an indefinite number of sectional headers, thus securing a larger range of capacities from single built-up units, and it will be moreover apparent that by reason of the large number of independent parts which are employed to make up the sectional boiler repair thereof is greatly facilitated, as but a small portion of the whole unit would be deranged by the breaking of a single part. Another important advantage realized in my construction is that while maintaining the common level between the steam and water drums the circulation of the water through the boiler may be increased to any desired extent by merely lengthening the connecting-tubes which are extended between the rear steam and water drum and the sectional headers arranged thereunder or by shortening the tubes connecting the front series of sectional headers with the steam and water drums arranged thereabove.

As many changes could be made in the above construction and many apparently widely different embodiments of my invention could be made without departing from the scope thereof, I intend that all matter contained in the above description or shown in the accompanying drawings shall be interpreted as illustrative and not in a limiting sense. I desire it also to be understood that the language used in the following claims is intended to cover all of the generic and specific features of the invention herein described and all statements of the scope of the invention which as a matter of language might be said to fall therebetween.

Having described my invention, what I claim as new, and desire to secure by Letters Patent, is—

1. In a water-tube boiler, the combination

of a plurality of headers arranged at either end thereof, a series of water-tubes extended between oppositely-disposed headers, a steam and water drum extending transversely of said water-tubes above the same at either end of the boiler, separate risers connecting said headers with the steam and water drum above the same, a plurality of equalizer-tubes connecting said drums, a steam-drum arranged intermediate the steam and water drums, and a plurality of tubes arranged above the water-line for connecting said drum with one of said steam and water drums.

15 2. In a water-tube boiler, the combination of a series of water-tubes disposed in staggered vertical rows, a plurality of sinuous sectional headers, one of said headers being arranged at either end of each row of said

water-tubes, and between which said tubes extend, a steam and water drum extending crosswise of said water-tubes at either end of the boiler, a tube or riser extending between each of said sinuous headers and the steam and water drum above the same, equalizer-tubes extended in one or more horizontal rows between said steam and water drums, a steam-drum located intermediate the steam and water drums, and a plurality of tubes extended between said steam-drum 30 and said steam and water drums, said tubes being arranged above the water-line.

In testimony whereof I affix my signature in the presence of two witnesses.

FRANK Z. SHERER.
